(57) **CLAIM**

The ornamental design for a “flow meter end fitting with integral tube connector”, as shown and described.

DESCRIPTION

FIG. 1 is a perspective view of a flow meter end fitting with integral tubing connector showing my new design;

FIG. 2 is a right side elevational view, left side elevational view and the bottom plan being a mirrored image thereof;

FIG. 3 is a front elevational view thereof;

FIG. 4 is a rear elevational view thereof; and,

FIG. 5 is a top plan view thereof.
